UNITED STATES PATENT OFFICE.

OTTO PETERMANN, OF GROTON, NEW YORK, ASSIGNOR TO CORONA TYPEWRITER COMPANY, INC., OF GROTON, NEW YORK, A CORPORATION OF NEW YORK.

TYPEWRITING MACHINE.

Application filed July 28, 1920. Serial No. 399,567.

To all whom it may concern:

Be it known that I, OTTO PETERMANN, a citizen of the United States, and resident of Groton, in the county of Tompkins and 5 State of New York, have invented certain new and useful Improvements in Typewriting Machines, of which the following is a specification.

This invention relates to improvements 10 in typewriting machines, and more particularly to means for supporting and guiding the type-bar segment in typewriting machines in which the type-bar segment is shifted relatively to the platen for printing 15 characters of different case.

The invention has for its objects to provide a segment carrier and supporting and guiding means therefor, of simple, light, compact and inexpensive construction; to 20 provide improved antifriction supporting and guiding means for the segment carrier; and to provide segment carrying and guiding means which may be constructed of sheet metal, consists of a minimum number of 25 parts, and may be readily assembled in a machine frame. Further objects of the invention will appear from the description of the improvements in connection with the accompanying drawings.

30 In the drawings, Fig. 1 is a front elevation of the segment and the supporting and guiding means therefor, the segment and carrier being shown in the uppermost position thereof;

35 Fig. 2 a view similar to Fig. 1, showing the segment and carrier in the lowermost position thereof;

Fig. 3 a view similar to Fig. 1 with the segment removed;

40 Fig. 4 a top plan view of the parts shown in Fig. 3;

Fig. 5 a fragmentary vertical sectional view taken on the line V—V of Fig. 4; and

45 Fig. 6 a fragmentary vertical sectional view taken on the line VI—VI of Fig. 4.

The main frame of the machine is preferably formed of pressed steel as shown in the drawings, in which 1 designates the rear wall or plate of the frame and 2 designates the side walls thereof. A pair of sheet 50 steel guide members are detachably held to the front face of the rear wall 1 of the machine frame at points adjacent opposite sides of the frame, by screws 3 which pass through the rear plates 4 of said members.

An integral angular carrier-guide 5 extends forwardly from the outer edge of each plate 4 a short distance, and is then bent inwardly at right angles and widened vertically at its inner end at 6. Each plate 4 of the guide 60 members is provided with a pair of angular carrier-guides or retainers 7 which extend forwardly from the inner edge of the plate at points above and below the adjacent guide 5 and are bent inwardly at 65 right angles. The guides 5 are relatively wide vertically, while the guides 7 are comparatively narrow vertically. The inwardly extending arms of the guides 7 are located in a vertical plane at the rear of the 70 plane of the guides 5 and do not extend inwardly toward the longitudinal center of the machine frame as far as the inwardly extending arms of guides 5.

The segment carrier 8 comprises a flat 75 sheet steel plate cut away intermediate its ends at its upper edge along a line corresponding substantially with the curvature of the type-bar segment 9. The segment 9 is detachably held to the carrier plate 8 80 by screws 10 extending through apertures 11 in the plate 8 from the rear face of said plate and threaded into lugs 12 formed on the opposite ends of the segment. The vertical side edges of the carrier plate 8 lie 85 closely adjacent the inner sides of the forwardly extending portions of the angular guides or retainers 7, and the front face of the plate 8 lies closely adjacent the rear sides of the inwardly extending portions 90 of said guides 7, the plate being, however, normally out of contact with said guides which serve to prevent sidewise, forward or rocking movements of the plate when the plate or parts connected therewith are subjected to shocks or excessive pressure.

Any suitable key-operated means may be provided for moving the segment carrier 8 vertically relatively to the machine frame to shift the segment 9 relatively to the 100 platen and thus change the case. The carrier is supported and guided to move vertically with a minimum of friction, by a four-point antifriction supporting and guiding means. A vertically extending 105 raceway member 13 formed of sheet metal and substantially V-shape in cross section is secured to the front face of the rear wall 1 of the machine frame by a pair of screws 14, said raceway member being located mid- 110

way the ends of the wall 1 with its raceway channel facing forwardly. A complementary vertically extending sheet metal raceway member 15 of the same shape and substantially the same length as the raceway member 13 is secured to the rear face of the carrier plate 8 by two pairs of screws 16 and 17 the ends of which project into the ball race formed by the channels of the members 13 and 15. The two screws 17 are spaced apart the same distance as the two screws 16 and the inner ends of screws 17 serve to limit the travel of a ball 19 in the raceway, while screws 16 serve to limit the travel of a ball 18 in the raceway. The pairs of screws 16 and 17 are located respectively above and below the longitudinal center of the carrier plate.

A pair of short, vertically extending raceway members 20 are secured to the front face of the carrier plate in the rear of the vertically widened ends 6 of the carrier guides or angular brackets 5. The raceway members 20 are of rectangular, vertically elongated, box-like form, being preferably stamped or pressed up from a suitable sheet metal blank, and are preferably secured to plate 8 by welding the bottoms of the box-like raceway members to the front face of the carrier plate. The members 20 are shorter vertically than the ends 6 of members 5 with which they cooperate to form ball races for two balls 21. The members 20 are located substantially midway the upper and lower edges of the plate 8 with their lower edges in a plane substantially midway between the lower screw 16 and the upper screw 17, so that the balls 21 are located adjacent the side edges of and at the opposite face of the carrier plate from the balls 18 and 19 and in a horizontal plane substantially midway between the horizontal planes in which said balls 18 and 19 are located. This relative relationship of the four ball bearings being maintained at all times. It will be obvious that this arrangement of four-point antifriction bearing affords a simple antifriction supporting and guiding means for the carrier plate which permits direct vertical movement of the plate with a minimum of friction, and also prevents movement of the plate in any other direction. Rocking of the plate in either direction about a vertical axis is prevented by the bearing portions 6 of the angular guides 5 over the inner face of which the balls 21 travel. Rocking of the plate in either direction about a horizontal axis is prevented by the arrangement of balls 18 and 19 above and below balls 20 and at the opposite face of plate 8 from balls 20. Transverse or sidewise movement of the carrier plate is resisted by engagement of balls 18 and 19 with the sides of the channel raceway members 13 and 15. The members 5, as above described, are

formed of thin sheet steel, and the inwardly extending arms thereof provided with the widened bearing portions 6 are sufficiently resilient to permit them to be adjusted or flexed fore and aft of the machine relatively to the carrier plate and held in adjusted position by bolts 22 and nuts 23. The shanks of bolts 22 pass through the frame wall 1 and the base plates 4 of the carrier guides, and through apertures in the inwardly extending arms of the angular brackets 5, and it will be obvious that by threading nuts 23 on the bolts the inwardly extending resilient arms of brackets 5 may be flexed or forced rearwardly sufficiently to bear against balls 21 under spring tension. This adjustment of the front ball-engaging members 6 against the front balls under spring tension provides means for automatically taking up wear in the rear center bearings as well as in each of the forward bearings since the tendency of the resilient arms is to constantly press the front balls 21 and the segment carrier toward the rear. The independent adjustment of the bearing arms 6 fore and aft of the machine and the arrangement of center bearings at one face of the carrier and two bearings at the other face of the carrier adjacent its side edges, permit adjustment of the carrier about a vertical axis located centrally of the carrier to align the carrier and segment and the usual type-bar-pivot wire in the segment parallel with the printing line of the platen.

It will be observed also that, while the rear center-bearing raceway members 13 and 15 are of channel form and balls 18 and 19 engage both sides of the channels in said members, the ball pockets 20 have flat bottoms or vertical surfaces along which the balls 21 roll and vertical forwardly extending side walls spaced apart a greater distance than the diameter of balls 21. This arrangement and construction of the three sets of ball races avoids the necessity of close adjustments in assembling the mechanism, or extreme accuracy in manufacture of the parts, to make the carrier travel vertically without friction.

What I claim is:

1. In a typewriting machine, the combination of a support shiftable edgewise to change case, a centrally arranged guide at one face of the support, resilient guides spaced apart transversely of the path of movement of the support at the other face of said support and located at opposite sides of the centrally arranged guide, rolling elements between the opposite faces of the support and said guides, and adjustable means for holding the resilient guides against the rolling elements contacting therewith under tension.

2. In a typewriting machine, the combination of a machine frame, a support shift-

- able edgewise in an up and down direction in the frame to change case, vertically spaced rolling elements located centrally of the support at one face of said support, horizontally spaced rolling elements at opposite sides of the vertically spaced elements and located at the other face of the support, raceway members on the frame at the opposite faces of the support between which and the support the rolling elements travel, and means for adjusting the raceway members at opposite faces of the support relatively to each other fore and aft of the machine.
- 15 3. In a case shift mechanism, the combination of a support shiftable edgewise to vary the relation between type-carrying means and a platen, a pair of rolling elements spaced apart longitudinally of the path of movement of the support and located at one face of the support substantially midway the side edges of the support, a pair of rolling elements spaced apart transversely of the path of movement of the support and located at the other face of the support at opposite sides of the first pair of rolling elements and in a plane passing between said first two rolling elements, and guiding means between which and said support said elements roll.
4. In a typewriting machine, the combination with the frame thereof, of a sheet metal carrier plate vertically shiftable edgewise in the frame, a type-bar segment held to said plate, a pair of vertically spaced balls arranged at the rear of said plate in a plane midway the side edges thereof, a pair of balls spaced transversely of the frame arranged at opposite sides of the center of the plate at the front thereof in a horizontal plane intersecting the plane of the vertically spaced balls at a point between said vertically spaced balls, and means on the plate and frame forming vertical races for both pairs of balls.
5. In a typewriting machine, the combination of a frame, a type-segment, a support for the segment shiftable up and down relatively to the frame, a four-point anti-friction support for said carrier, two of said points of support resisting rearward and sidewise movements of the carrier and the other two of said points of support yieldably resisting forward movement of the carrier, and means mounted in the frame for preventing excessive sidewise and forward movements of the carrier.
6. In a typewriting machine, the combination of a frame, a vertically shiftable segment support, a vertically extending member held to the rear side of said support midway the ends of the support and provided with a longitudinal raceway channel, a complementary vertically extending member held to the frame and provided with a raceway channel, a pair of vertically spaced balls in the raceway formed by said members, means held to the frame and support forming two vertical raceways at the front side of the support at opposite sides of the center of the support, and a ball in each of the raceways at the front of the segment support.
7. In a typewriting machine, the combination of a frame, a sheet metal carrier plate shiftable up and down edgewise in the frame, a type-bar segment mounted on the plate, complementary vertically extending raceway members held to the frame and carrier midway the sides of the frame and so provided with ball channels, a pair of spaced balls traveling in the upper and lower parts respectively of the raceway formed by said members, a pair of sheet metal brackets held to the frame at opposite sides thereof having flat guide arms projecting in front of the carrier plate, a pair of raceway members held to the front of the plate to move therewith in rear of the bracket arms, a ball interposed between the inner face of each bracket arm and the adjacent channel raceway member on the front of the plate, and means for adjusting the guide arms of the brackets fore and aft of the machine.
8. In a typewriting machine, the combination of a frame, a support shiftable edgewise in the frame to vary the relation between type-carrying means and a platen, two complementary raceway members located substantially midway the side edges of the support at one face of the support and movable with the frame and support respectively and having V-shaped ball channels therein, balls in the raceway formed by the channels in said members and each engaging both sides of the channels, and means located at the opposite face of the support at opposite sides of the center of the support forming ball raceways having flat ball-engaging surfaces parallel with the plane of movement of the support and side edges at an angle to the plane of movement of the support, and balls in said last-mentioned raceways of less diameter than the width of the raceways.
9. In a typewriting machine, the combination of a machine frame, a support shiftable edgewise up and down in the frame to change case, a pair of vertically spaced rolling elements located centrally of the support at one face of said support, a pair of horizontally spaced rolling elements located at the opposite face of the support and arranged at opposite sides of the vertical center line of the support, and raceway members on the frame at opposite faces of the support between which and the support said rolling elements travel, the raceway members being yieldable relatively to each other fore and aft of the machine.

10. In a typewriting machine, the combination of a support shiftable to change case, two guiding means at one face of the support spaced apart transversely of the path of movement of the support, guiding means at the opposite face of the support on which the support is adapted to rock about an axis extending in the direction of its case-shift movement and located intermediate the transversely spaced guiding means, and means for independently adjusting the transversely spaced guiding means toward and from the support. 15. In a typewriting machine, the combination of a frame, a support shiftable edge-wise in the frame to change case, antifriction guiding means at one face of the support, resilient members rigidly held at their outer ends adjacent opposite sides of the frame, antifriction rolling elements interposed between the inner ends of said members and the opposite face of the support, adjustable means for flexing the inner ends of said resilient members toward the adjacent face of the support and holding the same in flexed condition against said rolling elements, and means on the frame coacting with said support for limiting movement of the support toward the resilient members. 70
11. A shift frame for typewriting machines provided at two oppositely disposed faces thereof with means for receiving antifriction rolling elements and guiding the same in parallel lines with the rolling elements at one face thereof on a line extending transversely of the path of movement of the support between rolling elements at the opposite face of the frame. 16. In a typewriting machine, the combination of a shift frame movable edgewise to change case, antifriction rolling elements at one face of said frame spaced apart longitudinally of the path of movement of the frame and located substantially midway the sides of the frame, rolling elements at the opposite face of the frame at both sides of the first mentioned rolling elements, and relatively yieldable guides at opposite faces of the frame between which and said frame the rolling elements travel. 75
12. A shift frame for typewriting machines provided at one face thereof midway its sides with means for guiding a pair of antifriction rolling elements spaced apart longitudinally of the path of movement of the frame, and provided at its opposite face with means for guiding a pair of antifriction rolling elements spaced apart transversely of the path of movement of the frame and located at opposite sides of the first-mentioned guiding means. 17. In a typewriting machine, the combination of a main frame, a substantially flat case shift frame shiftable edgewise up and down in the main frame and located closely adjacent the rear wall of the main frame, a central antifriction guide between the rear face of said shift frame and the rear wall of the main frame, and transversely spaced antifriction guides located at the front face of the shift frame, said guides all being supported on the rear wall of the main frame. 80
13. In a typewriting machine, the combination of a frame, a support shiftable edge-wise in the frame to change case, means forming a ball channel on one face of said support midway the sides of the support, means on the frame forming a complementary ball channel, balls rolling in the raceway formed by said channels and resisting sidewise movement of the support as well as movement of the support toward the channel on the frame, means forming ball channels on the opposite face of the support at opposite sides of the center of the support, means on the frame cooperating with the last-mentioned ball channels to form raceways, and balls confined in said last-mentioned raceways and having a limited lateral play therein. 18. In a typewriting machine, the combination of a main frame, a relatively flat shift frame shiftable edgewise up and down close to the rear wall of the main frame and provided with races at the front and rear sides thereof, rolling elements in said races, and means supported on the rear wall of the frame between which and said races the rolling elements travel. 85
14. In a typewriting machine, the combination of a frame, a support shiftable edge-wise in the frame to change case, antifriction guiding means at one face of the support, resilient members rigidly held at their outer ends to the frame, antifriction rolling elements interposed between the inner ends of said members and the opposite face of the support, and adjustable means for flexing the inner ends of said resilient members relatively to the frame toward the adjacent face of the support and holding the same in flexed condition against said rolling elements. 19. In a typewriting machine, the combination of a main frame, a substantially flat segment carrier shiftable edgewise up and down close to the rear wall of the main frame, a type-bar segment held to the front face of said carrier and relatively yieldable guiding means for said carrier supported on the rear wall of the main frame. 90
20. In a typewriting machine, the combination of a main frame, a substantially flat sheet metal segment carrier shiftable edge-wise up and down close to the rear wall of the frame, ball races at the front and rear faces of said carrier extending up and down, balls in said races, and a plurality of sheet metal guides held to the rear wall of the 95

machine and extending up and down opposite the races on the carrier and holding the balls therein.

21. In a typewriting machine, the combination of a frame, a support extending transversely of the frame and shiftable edge-wise therein to change case, a rigid center guide member for the support held to the frame at one face of the support midway between the sides of the frame, a pair of resilient guide members rigidly held to the

frame and having portions thereof located at the other face of the support at opposite sides of the center guide and flexible toward and from the adjacent face of the support, and antifriction rolling elements interposed between the three guide members and the support. ¹⁵

In testimony whereof I hereunto affix my signature.

OTTO PETERMANN.
